UNITED STATES PATENT OFFICE.

JULIUS REINHARD DRODZEWSKI AND JOHN McCONNELL, OF ERIE, PA.

PRINTER'S QUOIN.

SPECIFICATION forming part of Letters Patent No. 326,484, dated September 15, 1885.

Application filed July 16, 1884. (No model.)

To all whom it may concern:

Be it known that we, JULIUS REINHARD DRODZEWSKI and JOHN McCONNELL, citizens of the United States, residing at Erie, in the county of Erie and State of Pennsylvania, have invented certain new and useful Improvements in Printers' Quoins; and we do hereby declare the following to be a full, clear, and exact description of the invention, such as will enable others skilled in the art to which it appertains to make and use the same, reference being had to the accompanying drawings, and to the letters of reference marked thereon, forming part of this specification.

15 Our invention relates to improvements in printers' quoins.

The objects of our invention are to construct a printer's quoin of three sections, the central of which is wedged-shaped, and the inner faces 20 of the outer sections inclined sufficiently so that when the three sections of the quoin are placed together the outer surfaces of the side sections will be parallel. The upper edges of these sections are provided with notches adapted to 25 receive a lever or wrench for operating the same, one or more of the three sections being provided with a longitudinal slot, through which a rivet is secured in the countersunk openings in the two outside sections, so that the 30 three sections of the quoin are thereby securely attached together. Other features of our invention appear hereinafter in the specification and claims. We accomplish this object by the mechanism illustrated in the accompanying drawings, forming a part of this specification, in which—

Figure 1 is a perspective view of our improved quoin, together with the lever or wrench for operating the same in position 40 thereon. Fig. 2 is a side elevation of one of the outside sections and the central section of the quoin, one of the outside sections being left off. Fig. 3 is a top view of our improved quoin. Fig. 4 is a cross-section of our improved quoin, on the line xx in Fig. 3, showing the countersunk-openings in the side sections for the heads of the rivets.

Like letters represent like parts in all the figures.

50 In Fig. 1, A represents a section of an ordinary printer's chase; B, the side-stick therein;

C C, the two outside sections of our improved quoin; C', the central section thereof.

In the construction of our improved quoin we make the central section, C', wedge-shaped, 55 and the side sections, C C, inclined on their inner, faces toward one end thereof, substantially as shown in Fig. 3, the central of said sections C' being preferably constructed with the taper or wedge thereof equal to the incline 60 of both the side sections, C C. In the other direction the sections C C and C' are constructed substantially rectangular in shape. The central section, C', is provided with a longitudinal slot, D, extending nearly the whole 65 length thereof, as illustrated in Fig. 2. However, the sections C C may be slotted instead, if desired.

The side sections, C C, preferably are provided with rivet-holes F F, countersunk, substantially 70 as shown in Fig. 4, so that the rivet E will pass through the slot D and the rivet-holes F F, as illustrated in Figs. 3 and 4, to secure the three sections C C and C' together, yet admit of the central section being moved upon the 75 rivet sufficiently to spread the two side sections apart until the heads of the rivets engage with the shoulders on the inner portions of the rivet-holes F F, this rivet being loose 80 in the holes F F, so that it will freely move back and forth therein.

The top edges of the sections C C may be provided with notches c c, &c., and the central section, C', with notches d d, &c., the notches c c, &c., being adapted to receive the projections on the lower end of the wrench or lever G used for operating the quoin, and the notches d d, &c., on the central section, C', adapted to receive the hinged dog g on the wrench or lever G used for operating the quoin, as illustrated in Fig. 1.

The lever or wrench G is provided with a handle, H, one end of which has a hammer-shaped head, I. The opposite end of the handle H is reduced in size, and is of suitable 95 size and shape to adapt it to be used as a shooting-stick when desired.

In operating this quoin it will readily be seen that the sections C C and C', being connected together by the rivet E, as hereinbefore described, are at all times prevented from being separated, so that no part of the quoin can be-

come mislaid or lost; but that the same may be placed between the chase and side-stick of a form with the notched side of the same up, and by forcing the central section, C', between 5 the side sections, C C, of the quoin by means of the wrench or lever G, as illustrated in Fig. 1, the side-stick may be tightened against a form placed in the chase A, and thereby firmly secured in position.

10 It is obvious to any one skilled in the art to which this invention appertains that the sections of this quoin operate upon each other on the principle of double wedges, and a very strong pressure can be secured therewith by 15 forcing the sections together, as hereinbefore described. To release the quoin it is simply necessary to reverse the lever or wrench G and force the central section back in the opposite direction from that in which it was tight- 20ened.

Having thus fully described our invention so as to enable others to construct and use the same, we do not broadly claim a printer's quoin consisting of three wedge-shaped sections 25 adapted to be operated by a wrench or lever, as hereinbefore described; neither do we claim, broadly, a wrench or lever adapted to operate the same; but

What we claim as new, and desire to secure by Letters Patent of the United States, is—

1. The combination, in a printer's quoin, of a central wedge-shaped section having a longitudinal slot therein, with two side sections, the inner faces whereof are inclined to fit the wedge-shaped central section, and having 30 countersunk rivet-holes therein, substantially as shown, and a loose rivet passing through said countersunk-holes and said slot, substantially as and for the purpose set forth.

2. The combination, in a printer's quoin, of 40 the central wedge-shaped section, C', provided with the longitudinal slot D, and notches d, and the side sections, C C, provided with countersunk rivet-holes F F, and notches c, with the loose rivet E, substantially as and for 45 the purpose set forth.

In testimony whereof we affix our signatures in presence of two witnesses.

JULIUS REINHARD DRODZEWSKI.
JOHN McCONNELL.
